CLAIM

The ornamental design for a funerary viewing tray, as shown and described.

DESCRIPTION

FIG. 1 is a perspective view of a funerary viewing tray showing our new design;

FIG. 2 is a front side elevational view of the funerary viewing tray of FIG. 1;

FIG. 3 is a rear side elevational view of the funerary viewing tray of FIG. 1;

FIG. 4 is a left side elevational view of the funerary viewing tray of FIG. 1;

FIG. 5 is a right side elevational view of the funerary viewing tray of FIG. 1;

FIG. 6 is a top plan view of the funerary viewing tray of FIG. 1; and,

FIG. 7 is a bottom plan view of the funerary viewing tray of FIG. 1.

The broken lines shown in the drawings illustrate portions of the funerary viewing tray that form no part of the claimed design. The dash-dot lines depict the boundaries of the claimed design and form no part of the claimed design.
